(57) **CLAIM**

The ornamental design for a pivot pin tool, as shown and described.

DESCRIPTION

FIG. 1 is a top exploded perspective view of a pivot pin tool showing our new design;

FIG. 2 is a top exploded view of the pivot pin tool;

FIG. 3 is a front exploded view of the pivot pin tool;

FIG. 4 is a bottom exploded view of the pivot pin tool;

FIG. 5 is a bottom exploded perspective view of the pivot pin tool;

FIG. 6 is a right side exploded view of the pivot pin tool;

FIG. 7 is a rear exploded view of the pivot pin tool;

FIG. 8 is a bottom exploded perspective view of the pivot pin tool; and,

FIG. 9 is a left side exploded view of the pivot pin tool.

The dash-dash broken lines are included for the purpose of illustrating portions of the pivot pin tool and form no part of the claimed design. The dot-long dash broken connection lines depict the path for assembly of the exploded components and form no part of the claimed design.

1 Claim, 9 Drawing Sheets
